(57) **CLAIM**

The ornamental design for a poster board, as shown and described.

DESCRIPTION

The file of this patent or application file contains at least one drawing executed in color. Copies of this patent or patent application publication with color drawing will be provided by the Patent and Trademark Office upon request and payment of the necessary fee, 37 CFR 1.84(a)(2)(iii).

The single FIGURE is a front view of a poster board showing my new design.

The claimed design is intended to support displays.

The poster board has no appreciable thickness and the side views are therefore not shown.
